SEWING MACHINE

Rowland Augustus Lincham and Frank Barton,
Leicester, England, assignors to United Shoe
Machinery Corporation, Borough of Flemington,
N. J., a corporation of New Jersey

Application March 19, 1937, Serial No. 131,847
In Great Britain April 28, 1936

30 Claims. (Cl. 112—62)

This invention is concerned with improvements in or relating to sewing machines, and is particularly, but by no means exclusively concerned with facilitating the sewing together of the uppers and soles of turnshoes off the last, by the use of a curved hooked needle machine.

Experience in sewing turnshoes has hitherto indicated that, if use is made alone either of an external work support or an internal work support to support a shoe throughout the entire sewing operation therearound, difficulties are apt to arise during the sewing operation due, for example, to the fact that an external work support is liable to bend or distort the upper around the heel end of the shoe in an undesired manner over the sole during the feeding of the shoe past the support and to the fact that an internal work support is liable, particularly when it is given substantial falling movements between successive stitches, to pull the shoe upper away from the sewing point as the sewing proceeds around the forepart of the shoe.

In the patent to Fred Ricks No. 2,067,649 dated January 12, 1937, there is disclosed an arrangement of exchangeable internal and external work supporting devices which, with the object of allowing the said difficulties to be overcome, facilitates the use, during the sewing operation on the heel end and forepart portions, of a single shoe of either the internal or external work support as may then seem most appropriate.

One of the various objects of the present invention is to provide, as an alternative arrangement to that last referred to, an external work supporting device for supporting a shoe during the whole of the sewing operation thereon, and which is of such a nature that such difficulties as have been most commonly experienced hitherto when using external supports of usual types are obviated.

Further, when sewing together the uppers and soles of turnshoes by such curved needle machines as have been most generally used for this purpose, difficulty has been experienced in controlling and supporting the margins of the sole and upper with sufficient accuracy to ensure that the needle is caused to penetrate the work at a constant short distance from the edge of the shoe bottom during the formation of successive stitches, and this is liable to give rise to the disadvantage that the seam is not spaced uniformly from the edge of the shoe bottom all around the shoe.

Another of the various objects of the present invention is to provide means able to control and

support the work in such a definite relation to the path of the needle throughout the sewing operation that this difficulty also will be overcome.

Moreover, the present invention has for another of its objects to provide improved upper-engaging means which will be able to afford particular effective support to the work during the sewing operation and will assist in pressing the margin of the upper closely against the sole before it is sewn to the latter and in supporting said margin against being lifted away from the sole and possibly torn by the needle when the latter retreats from the work.

Still further objects of the present invention are to make provision, in a high speed sewing machine embodying a curved needle of relatively short radius, for ensuring that a looper for laying thread in a barb of the needle will, as it is actuated, move in such a path that its thread guiding eye will lay the thread unfailingly in the barb and, where the feed of the work through a machine is effected by a needle movable laterally through variable distances to effect this, to insure that a work-supporting foot for engaging the work close by the side of the needle shall always occupy a constant position by the side of the needle when the latter moves to penetrate the work in spite of any adjustment which may be made in the lateral position which the needle occupies at this time.

With the above and other objects in view, the present invention contemplates, inter alia, the provision in a curved needle sewing machine suitable for sewing together the uppers and soles of turnshoes, of a rising and falling external work support which, as it falls to facilitate the feeding of the work through the machine between successive stitches and, while the shoe is supported by the needle, moves also away from the shoe in a direction transversely to the path in which it rises and falls so as to remove it entirely from contact with the shoe during the movement of the shoe past the work support; of a sole engaging foot for supporting the shoe against the upthrust of the external support, which foot is arranged normally to project between the margins of the upper and sole substantially right up to the edge of the sole and is so mounted as to facilitate its withdrawal far enough from between the upper and sole as to permit the stitches initially made in the upper and sole at the commencement of the seam to pass by the said foot, and once more to reach the sewing point as the end of the sewing operation is approached in order that the beginning and end of the seam may

50

55

overlap somewhat to ensure the complete securing of the upper and sole together; of an upper pressing claw for engagement with the upper at the opposite sides of the needle which claw moves laterally with the needle as the latter acts to feed the work, is raised and lowered to cause it to engage and retire from engagement with the margin of the upper and is locked against rising or falling movement once it has properly pressed the upper margin against the sole; of a pendulous looper arrangement which is so arranged that the thread guiding eye of the looper moves, in laying the thread in the barb of a curved needle of relatively short radius, in a path more or less perpendicularly to the direction in which the pointed end of the needle then extends; and of a mounting for the sole engaging foot which is carried upon a member movable laterally with the needle when the lateral position of the needle is adjusted to control the length of needle feed so that the said foot and needle retain their lateral relation unaltered whatever be the length of needle feed, and of an upper pleating device, the position of which in the line of feed also can be adjusted simultaneously with the adjustment of the lateral position of the needle.

In order that the various objects and several features of the present invention (which latter are set forth in the appended claims) may be more fully understood, illustrative embodiments thereof will now be described with reference to the accompanying drawings of which:

Figure 1 is a front view of a machine embodying the several features of the invention;

Figure 2 is a right hand side view, partly in section, of the principal working parts of the machine;

Figure 3 is a right hand side view of certain upper pressing means;

Figure 4 is a plan view of the parts seen in Figure 3;

Figure 5 is a front view with the work shown in section, illustrating the relation of certain work supporting members and other parts of the machine;

Figure 6 is a plan view of certain parts seen in Figure 5 with the sole engaging foot in a different position;

Figure 7 is a front view of the head of a second machine embodying certain features of the invention in a somewhat different form;

Figure 8 is a front view of certain parts of the machine illustrated in Figure 7;

Figure 9 is a right hand side view of a sole engaging foot hereinafter described and also seen in Figure 7;

Figure 10 is a right hand side view of certain parts seen in Figure 7;

Figure 11 is a right hand side view of a channel engaging foot and parts associated therewith and which will be hereinafter described;

Figure 12 is a view in side elevation, partly in section, of a modified form of external work supporting structure which may be used in the place of that illustrated in Figure 2;

Figure 13 is a front view of the parts illustrated in Figure 12;

Figure 14 is a detail plan view, partly in section, of certain of the parts illustrated in Figure 12; and

Figure 15 is a detail front view, partly in section, of certain of the link connections at the lower end of the work support.

The machine illustrated in Figures 1 to 6 in numerous respects is similar to that disclosed in

the patent hereinbefore referred to, the machine including a curved hook needle 1 of small radius, needle guide 3, looper 5 and pleater 7, all supported and arranged to be actuated in a manner substantially the same as disclosed in said patent. The machine also includes an upper pressing member in the form of a claw 9 hereinafter described.

In the machine illustrated in Figures 1 to 6, however, the arrangement of interchangeable internal and external work supporting devices disclosed in said patent is dispensed with, though certain parts of the mechanism for automatically raising and lowering the support for said devices in time relation to the progress of the sewing operation and for adjusting it heightwise of the machine are retained.

The machine illustrated in Figures 1 to 6 includes a bracket 11 having a vertical bore, a vertical sleeve 13 normally stationary in said bore, a second sleeve 15 in the sleeve 13 together with an adjusting screw 17 coupling the two sleeves together, a vertical spindle 19 in the sleeve 15, a cam lever 21 for imparting rising and falling movements to the spindle 19 in time relation to the formation of the stitches in the work and a rod 23, spring 25 and a cam lever 27 for transmitting the necessary rocking movements to the lever 21. These parts are similar to the corresponding parts of the machine disclosed in said Patent No. 2,067,649. The sleeve 15 is coupled to a treadle to facilitate depression of the spindle 19 to an unusually lowered position prior to, and at the end of the sewing operation on a shoe, to expedite the presentation of a shoe to the machine and its removal from the machine, through means which may be assumed to be identical with that disclosed in said patent. The machine also includes an edge gauge 29 like that disclosed in said patent.

Instead, however, of the vertical spindle 19 of the present machine supporting a U-shaped member presenting both internal and external work-supporting devices, it has pivoted on its upper end, on coaxial pivot pins 31 extending transversely, i. e., widthwise of the machine, an external work support 33 only. This support is bowed rearwardly between its upper and lower ends and at its upper end has adjustably secured in a horizontal dovetail guideway extending forwardly and rearwardly of the machine, a rectangular block 35. The upper face of the block 35 normally extends in a horizontal plane, is arranged to press a portion of the shoe upper A against the underface of the sole B and has teeth extending widthwise across it to enable it to grip the work the more firmly.

When the external work support 33 is in its operative position, the vertical axis of its supporting spindle passes through the central portion of the block 35, the rear end of which is arranged to provide but a relatively small gap between it and the operative face of the edge gauge 29. By slackening a set screw which clamps the block in its guideway, the block may be adjusted rearwardly to support the work as close up to the edge gauge as circumstances may permit. The axis 37 about which the needle rocks to pierce the work also lies in the same vertical plane, looked at from the side of the machine, as the axis of the vertical spindle 19 and, therefore, the block 35 will afford support to the work over substantially equal areas both forwardly and rearwardly of the needle axis, this ensuring that

the work will be well supported both in the locality where the needle strikes into the work and where it emerges through it.

If the block 35 on the support 33 were allowed to retain the forward and rearward position indicated when the spindle is lowered in each machine cycle to facilitate the feeding of the work through the machine by the needle, it would be likely to happen that, as the work is moved from right to left through the machine, the block would engage a depending portion of the upper, though not clamping it against the sole, in such a manner that it would tend to sweep the upper continually towards the right relatively to the sole, and this would considerably increase the difficulty of sewing the upper accurately to the sole, particularly around the heel end of the shoe where the upper may be relatively stiff owing to the presence of a back seam. With a view to eliminating this possibility, the external support 33 is arranged to be swung rearwardly, as it descends, to such an extent that the block 35 is sufficiently removed from the vicinity of the upper as not to contact with the latter as the needle carries the work through the machine.

For this purpose the external support 33 has projecting forwardly from its lower end (which is bifurcated) i. e. forwardly of its pivotal connection 31 with the spindle 19, a pair of toes 39 which have horizontal underfaces arranged, when the support is in its raised and operative position, as shown in Figure 1, to lie flat against corresponding faces formed on the upper end of the spindle 19 and thus both to limit the extent to which the support 33 can swing forwardly about its pivot and to afford support to the support 33 against downward thrust thereon.

Near their forward ends the toes 39 have a horizontal pin 41 passing transversely across them, which pin has a cam roll 43 freely mounted thereon between the toes so as to engage in a cam slot 45 formed along the upper end of a rocking cam plate 47 lying partly within the bifurcated lower end of the work support 33. The cam plate is pivotally mounted on a horizontal pin 49 extending transversely through the spindle 19 directly below the pin 41 in the toes 39 of the external support 33. The lower portion of the cam plate extends forwardly and downwardly somewhat from its pivot pin 49 and, at a slightly lower lever than and forwardly of the latter, its forward end portion receives a horizontal and transverse pin 51, the opposite ends of which are secured in the bifurcated forward end of a lever 55, which extends rearwardly past the opposite sides of the spindle 19 and is pivotally mounted on a horizontal transverse pin 57 fixed in the upper end of the normally fixed sleeve 15 rearward of the pivot pin 49 for the cam plate 47. The lever 55 extends rearwardly of its pivot pin 57 and at its rear end is pivotally connected to a depending and rearwardly bowed link 59 which is pivoted at its lower end on a transverse horizontal pin 61 secured in ears 63 projecting from the normally fixed sleeve 13, said pin also serving as a pivot for the upper link 65 of a toggle device 65, 67 similar to the toggle device disclosed in Patent No. 2,067,649. The distances from the forward and rearward ends of the lever 55 to the pivot pin 57 are proportional to the distances from the forward and rearward ends of the cam lever 21 to the pivot 69 for that lever so that vertical adjustment of the sleeve 15 carrying the pivots 57, 69, e. g. to suit the height of the external support 33 as may be required for different

thicknesses of work, will not cause the cam plate 47 to rock angularly about its pivotal connection with the spindle 19.

When the external work support 33 is in its normal operative position, the roll 43 between the toes 39 of the work support lies near the rear end of the slot 45, this being the position the roll occupies when the support is in raised position pressing the work upwardly against a sole-engaging foot 71 hereinafter described during the piercing 10 of the work by the needle 1. When, however, the spindle 19 is drawn downwardly, after the needle has pierced the work, to release the upward pressure of the support on the work to enable the needle to feed the work through the machine the more easily, the pivot pin 49 which connects the cam plate 47 to the spindle 19 moves downwards 15 simultaneously with the external support. The pin 51 which passes through the forward portion of the cam plate and is supported by the lever 55, however, remains in relatively fixed heightwise position during the rising and falling movements of the spindle.

Therefore as the spindle descends the cam plate rocks simultaneously rearwardly. During the greater portion of the downward movement of the external support 33, a portion of the cam slot 45 which is concentric about the pivot for the cam plate moves rearwardly along the roll 43 between the toes 39 of the external support and maintains the latter in its normal upwardly extending position. Just before the work support reaches its fully lowered position, however (e. g. when it has descended some half an inch) a straight portion at the forward end of the cam slot commences to move past the roll 43. When this commences, the cam plate will have been swung so far rearwardly that this straight portion lies at a considerable angle (e. g. an angle of some thirty or more degrees to the horizontal) 40 and during the concluding portion of the downward movement of the work support and spindle, the cam plate rocks rearwardly a further distance sufficient to raise the roll 43 in the toes of the support a substantial distance and thus to 45 rock the work support rearwardly about the pivot pin 31 which connects it to the spindle 19. The proportions and sizes of the various parts may conveniently be such that the support is first caused to descend in a vertical path, indicated at 50 X in Figure 2, for some half an inch and then, with but little further descent, is caused to move rearwardly in a substantially horizontal path, indicated at Y, some three quarters of an inch or so, the upper end of the work support actually 55 passing rearwardly between and being shrouded by bifurcated lower portions of the edge gauge 29.

The pivot 31 on which the support swings is provided by a pair of pins projecting outwardly from the opposite sides of the bifurcated lower 60 portion of the support 33, and positioned rearwardly of the position which the work engaging end occupies when the work support is in operative position, and this fact causes the work engaging end to rise somewhat as it swings rearwardly, thus largely nullifying the small amount of downward movement of the work support which takes place as it swings and allowing the work engaging end to move rearwardly substantially in a horizontal path as above indicated. 70

When, for the formation of the next stitch, the spindle 19 is raised to lift the work support, the first action of the rising spindle is to cause the cam plate 47 to rock forwardly and thus to swing the support from its rearwardly canted position 75

forwardly into its upright position, it being then raised vertically to press the work against the sole-engaging foot 71. As the work support swings forwardly and rises, its work engaging end follows the same right-angle path as it describes when the spindle is lowered.

By thus arranging for the work support to retire rearwardly during its descent and to swing forwardly during its ascent, the result is likely to be achieved that no contact between the support and work occurs during the feeding of the work by the needle, thus obviating any tendency for the support to sweep or fold the upper in an undesired manner on to the sole, and that, as the work engaging end of the support swings forwardly prior to engaging the upper after the feeding of the work, it will assume a convenient position relatively to the shoe upper which will enable it, when it rises into contact with the upper, to press flat against the sole that particular portion of the upper which is next to be sewn to the sole.

The fact that the actual work engaging face of the support extends substantially up to the work contacting face of the edge gauge ensures that the margin of the work will be firmly supported substantially right up to the edge thereof thus preventing downward bending of the margin by the work-penetrating action of the needle and assisting in the formation of the seam on the work at a constant short distance away from the edge of the shoe bottom.

The sole-engaging foot 71 previously referred to, against which the work is pressed upwardly by the work support, is arranged more or less directly over the work engaging face of the latter and its lower face provides a work-engaging face lying parallel with that of the work support. The foot is formed on the lower end of a stem 73 which extends upwardly and forwardly away from the foot at an angle of about thirty degrees to the vertical, it actually being carried on the lower end of an upstanding lever 75 which is normally latched rigidly in a fixed position. In order to support the foot 71 on the lever 75 and to provide capacity for adjusting the foot relatively thereto in various senses, the lower end of the lever has a relatively long horizontal bore extending forwardly and rearwardly through it in which is slidably mounted a shank 77 of a carrier block 79 for the foot. This block is secured on the forward end of the shank 77 and has a pair of upwardly extending ears 81 formed on it, which ears are spaced apart and closely embrace the opposite sides of a fin 83, extending forwardly and rearwardly of the machine, on the lever 75, this arrangement preventing rotation of the block 79 about the axis of the shank 77 while providing capacity for forward and rearward sliding adjustment thereof. The block 79 has a T-shaped guideway extending horizontally and transversely across it in which guideway is housed a slide 85 carrying on its forward side a slideway 87 extending, at right angles to the T-shaped guideway, upwardly and forwardly at an angle of some thirty degrees to the vertical.

The stem 73 of the sole engaging foot 71 is received within the slideway 87 and a clamping bolt 89 passing through a slot in the stem and into the slide 85 provides a means whereby the foot may be clamped rigidly in position after the foot has been adjusted either laterally or heightwise to suit any particular kind of work. The stem 73 of the foot has a horizontal groove 75 extending transversely across its rear face near

its upper end and a stud 91, arranged parallel to the stem and having a peripheral flange engaging in said groove, threaded into the block 79 may be rotated to adjust the heightwise position of the foot when the said clamping bolt 89 has been loosened. The path which the point of the needle makes just as it emerges through the work at the end of its work penetrating stroke extends forwardly and upwardly more or less parallel to the stem of the foot and by arranging for the foot to be adjusted upwardly and downwardly at the angle indicated there is provided a means whereby adjustment in the heightwise position of the foot may take place without causing a portion of the foot extending across the front of the needle to move forwardly or rearwardly to any marked extent relatively to the part of the needle which emerges through the work, thus allowing the foot to engage the work as close as possible to the needle in spite of the adjustment of the foot.

As seen from above, the foot 71 is somewhat L-shaped in plan, it having a rearwardly extending portion arranged to lie close by the right hand side of the needle, as the latter pierces the work, with its left hand edge substantially parallel to the plane in which the needle rocks and another portion, lying substantially perpendicularly to the first mentioned portion, arranged to extend towards the left of the machine so far that its left hand end lies almost in the same plane, considered forwardly and rearwardly of the machine, as the needle when the latter has moved as far over towards the left as it can in feeding the work. The rearward edge of this second portion of the foot lies parallel to the path of work feed, and is arranged to lie as close as possible to the position at which the needle emerges through the work so that the work is supported from above by the foot both as close as possible to the position at which the needle pierces the work and at the position at which the needle emerges through it, thus affording support to the work in places where such support is likely to be most advantageous. Both portions of the foot have a substantial area of contact with the sole to increase the efficiency of the foot in determining the heightwise position of the sole.

The rearwardly extending portion of the foot is arranged, as indicated in Figures 2 and 5, actually to project between the sole and the margin of the upper which is laid over the latter (it being sufficiently thin not to separate the upper appreciably from the sole) so as to afford the maximum support to upward bending of the margin of the sole and is preferably arranged to extend so far rearwardly as to lie near the edge of the sole when the shoe is in contact with the edge gauge. The vertical axis of the external support is displaced a short distance towards the right, looking at the machine from the front, from the plane in which the needle will lie at the end of its work-feeding movement, and owing to this fact, the work engaging face thereof will normally lie more or less directly beneath portions of the sole-engaging faces of the two portions of the sole-engaging foot, the overall length and width of the lower face of the foot being somewhat greater than that of the work engaging face of the block 35. Therefore, when the external support has risen to clamp the work against the sole engaging foot, the work will be clamped on both its upper and under faces between members which engage the work over extensive areas, hold its margin horizontally and against bending up.

wardly or downwardly, and maintain it in such a constant and predetermined position relative to the points at which the needle strikes into and emerges from the work that a seam, of constant width, is likely to be formed on the work at a constant distance from the edge thereof.

As has been stated, the rearwardly extending portion of the sole engaging foot extends rearwardly near to the operative face of the edge gauge, and since it is usually desirable that the end of the seam on the shoe may overlap the beginning somewhat to ensure that the upper will be adequately secured to the sole all around the latter, means is provided in the present illustrative machine for withdrawing the sole-engaging foot so far forwardly, when the beginning stitches of a seam once more approach the sewing point near the end of the sewing operation, that the beginning stitches may pass freely past the rear end of the rearwardly extending portion of the foot without being obstructed thereby.

For this purpose the block 79 which carries the sole-engaging foot is arranged to be slid forwardly relatively to the lever 75 which carries it and has a pair of recesses 93 formed in its opposite sides near to its upper face into which extend the lower and rounded bifurcated ends of a bell crank lever 95. This bell crank lever is mounted on the block-carrying lever 75 on a horizontal transversely extending pivot pin 97. A rearwardly extending arm 99 of this bell crank lever is coupled to the upper end of a downwardly extending link 101 which is pivotally coupled at its lower end to the forward end of a pivoted lever 103 which is arranged to be raised and lowered by the engagement of a pin 105 which it carries in a slotted cam member 107, secured to a rock shaft 108 to which rock shaft is also secured a hand lever 109 by the actuation of which the slotted cam member 107 may be rocked forwardly and rearwardly. This hand lever is acted upon by a toggle spring 110, and its movements in each direction are limited by stop shoulders at the rear end of the lever engaging a pin 112 mounted in the frame of the machine.

At the commencement of the sewing operation on a shoe and almost until the completion of the sewing operation, the hand lever 109 will occupy a raised position and the cam member 107 will occupy a backwardly canted position in which a raised portion of the cam slot therein engages the pin 105. The lever carrying the pin 105 will, therefore, also occupy a raised position about its pivot and the bell crank lever 95 to which it is coupled and which is connected to the block 79 supporting the sole engaging foot 71 will occupy a position about its pivot 97 in which its lower end is swung rearwardly, the sole engaging foot at this time lying in the fore and aft position indicated in Figure 2 in which the rearward end of its right hand portion extends near to the edge of the sole. That portion of the pin 105 which extends within the cam slot in the slotted cam member 107 is formed as an eccentric portion of a stud 111 which is rotatably mounted in the lever 103 and by rotating the stud 111 the heightwise position of the stud and, therefore, of the lever 103 which carries it, can be varied to adjust the precise forward and rearward position of the sole engaging foot as may seem desirable for any particular kind of work.

The foot is allowed to remain in this position until, near the end of the sewing operation, the first stitches made at the beginning of the seam once more approach the sewing point. In order

to allow these stitches to pass by the rear end of the foot, and in order that the foot may still give very effective support to the work during the formation of the last few stitches, the operator then swings the hand lever 109 controlling the slotted cam plate 107 downwardly and thus causes a lowered portion of the cam slot therein to engage the pin 105. This results in a short forward swinging movement being imparted to the downwardly extending arm of the bell crank lever 95 controlling the foot and results in the foot being drawn horizontally forward along the sole a distance sufficient to cause its rear end to lie somewhat forwardly of those portions of the thread uniting the upper and sole at the beginning of the seam which pass downwardly through the margin of the upper and into the sole. The position of the foot at this time is indicated in Figure 6. When the foot has been moved to this position, the shoe may be fed along by the needle during the formation of the few remaining stitches to cause the beginning and end of the seam to overlap and the stitches at the beginning of the seam may pass transversely across the rearward end of the foot without being obstructed by it.

The machine illustrated in Figures 1 to 6 includes a pleater 7 like that disclosed in Patent No. 2,067,649 and actuated by similar mechanism. Stated briefly, the pleater withdraws from over the work just about as the needle commences to move laterally to feed the work, advances again to form a pleat on the work just about as the needle reaches the end of its work-feeding movement and remains in its advanced position until the needle, after having retired from the work and moved idly towards the right, pierces the pleat formed by the pleater at which time the pleater retires from over the work. The pleater advances over, and forms the pleat against the right hand portion of the sole-engaging foot, as indicated in the drawings, the heightwise position of the pleater being conveniently adjusted to allow for the thickness of this portion of the foot lying between the sole and upper, by rotation of a vertical sleeve 113 supporting the guideway 114 in which it reciprocates, said sleeve being threaded into a fixed portion of the machine frame.

In order that the sole engaging foot may support the work most effectively against being moved forwardly by the action of the needle as it pierces the work, the underface of the foot conveniently has a number of serrations formed transversely across its work engaging face and a small downwardly and rearwardly extending tooth 115 projecting from it which is arranged to dig slightly into the sole to hold it more or less positively against forward movement. As the foot is moved forwardly by the operator in the manner previously described near the end of the sewing operation, the said tooth, by reason of its rearward inclination, slides over the sole without tending substantially to move the sole forwardly in the operator's hands.

The sole engaging foot 71 above described is particularly suitable for use on shoes, such as those having rubber, felt, or combination felt and leather soles, the soles of which are not provided with channel lips to which the uppers are to be sewn.

For use on shoes having soles, e. g. leather soles, having channels and channel lips it may be desirable to use in place of the sole engaging foot 71 a channel guide to enter the channel and 75

thereby both so to guide the work that the needle will pass through the upper and channel lip and also to support the sole against the up-thrust of the external support. The edge gauge 5 29 is then no longer needed and may be pushed rearwardly to an inoperative position after a clamping bolt has been loosened.

To this end the sole engaging foot 71 may readily be removed from the machine when the 10 bolt 89 which secures its stem to its supporting slide 85 is released and a channel guide, having a stem of the same shape and size as that of the sole-engaging foot, may be secured to the slide in its place. At its lower end the channel 15 guide stem is shaped similarly to the channel guide shown in Figure 11 of the accompanying drawings and is turned rearwardly and slightly downwardly to provide the channel guide proper, and the rear end of the guide, which is arranged 20 to engage in the channel and to abut against the root of the channel lip, is arranged to lie just to the right of the position where the needle penetrates the work and, as seen from the side of the machine, is arranged to lie directly below 25 the axis about which the needle rocks. This latter fact ensures that the shoe will be presented in the desired position forwardly and rearwardly of the machine for the needle to strike through the margin of the upper and the root of the 30 channel lip.

When using such a channel guide for supporting and guiding the work it is desirable that the guide be moved slightly forwardly in each cycle, before the needle commences to move laterally to feed the work, in order to facilitate the movement of the work through the machine. For this purpose, the lever 75 which supports the sole engaging foot 71 is arranged, when the channel guide has been substituted for the foot, to be released from its normally latched condition and 35 to be subjected to the action of a cam which thereupon allows its upper end, under the action of a spring, to rock rearwardly slightly about a pivot 117 at the appropriate time and, therefore, to move the channel guide slightly forwardly. 40 The said pivot for the lever extends transversely of the machine, substantially mid-way between the upper and lower ends of the lever 75 and the pin which connects the bell crank lever 95 to the downwardly extending link 101 normally occupies 45 a position in which it lies coaxially with the pivot 117 for the lever 75 so that the rocking movements of the latter will not cause any angular disturbance of the bell crank lever 95 about its pivot 97 and, therefore, disturb the forward and 50 rearward setting of the channel guide.

At its upper end the lever 75 has pivoted to it a rod 119 extending forwardly and upwardly of the machine which passes in front of the lever through a lug 121 extending upwardly from a 55 fixed bracket 123 on the machine frame. A spring 125 housed between the rear face of the lug 121 and a shoulder on the rod 119 tends to urge the upper end of the lever 75 rearwardly but is normally prevented from so doing by a 60 rotatable head 127 on the forward end of the rod which has tongues 128 extending from it, axially of the rod, the rear ends of which abut against the forward face of the lug and hold the 65 spring in compressed condition and the lever 70 75 normally latched in relatively fixed position. The lever is maintained in this condition when the sole-engaging foot is present in the machine but when the channel guide has been substituted 70 for the latter, the head 127 on the upper end of

the rod 119 is rotated through ninety degrees so that the tongues 128 thereon may enter rearwardly extending gashes 131 cut in the lug and thus allow the spring to urge the upper end of the lever rearwardly, and thereto to move the 5 channel guide forwardly at the appropriate time. At its upper end the lever 75 also carries a cam roll 133 which is engaged by the periphery of a cam 134 on the main shaft 135 of the machine. The periphery of this cam is, for the greater 10 part, concentric about the axis of its shaft but in an appropriate place thereon has a shallow depression therein which, when the spring 125 is allowed to act on the lever 75, allows the upper end of the lever to swing rearwardly, and therefore allows the channel guide to move forwardly, a small distance just before the needle, having penetrated the work, commences to move laterally. In order to limit the extent to which the lever 75 so swings an adjustable stop screw 137 passing 20 through the fixed bracket 123 is arranged to contact with the forward face of the lower portion of the lever. Obviously before the head 127 on the rod 119 is turned, the lever 75 is prevented from swinging about its pivot even when 25 the depression in the cam 134 comes opposite to it.

Thus, the machine is provided with convenient means whereby the sole-engaging foot may readily be replaced by a channel guide when desired 30 and whereby a lever for carrying the foot or the guide may be held against rocking movement when the lever supports the foot and may be released for cam actuated rocking movement when the channel guide has been assembled on 35 the lever.

The upper pressing claw 9 hereinbefore referred to assists in controlling the heightwise position of the work and presses the margin of the upper 40 firmly against the sole both when the needle strikes into the work and when it retreats from the latter. This upper pressing claw, as illustrated, comprises a member which, when looked at in plan, is narrow and substantially U-shaped with its limbs extending forwardly of the machine (see Figures 3 and 4) to engage the work close against the right and left hand sides of the needle. When using the U-shaped claw 9, the sole-engaging foot or channel guide must be adjusted so far toward the right of the machine 45 as to provide room between it and the needle for the right hand limb of the claw 9 to lie in.

The forward ends of the limbs of the claw lie, as seen from the side of the machine, slightly rearwardly of the axis about which the needle 55 rocks and the claw is, therefore, arranged, in the manner hereinafter described, to press against the margin of the upper from the edge of the shoe well forwardly over the margin. The upper pressing claw extends substantially horizontally, 60 rearwardly from its forward ends just over the top of the edge gauge 29 and is fixed, just behind the latter and substantially on the same level as the needle axis, on the right hand end of a horizontal transversely extending rod 141 65 which is slidable axially in a sleeve bearing formed in the forward end of a short forwardly and rearwardly extending lever 143. This lever extends rearwardly and slightly downwardly from its forward end to a fixed transversely extending 70 horizontal pin 145 on which it is pivoted.

Rearwardly of this pin, the lever extends upwardly and rearwardly and its rear end is slotted to receive a block 147 pivoted on the forward end of a cam-actuated lever 149 hereinafter described. 75

Through this lever the rod 141 supporting the claw 9 is lowered to carry the latter downwardly to press the upper margin against the sole and to raise the claw to relieve its pressure on the upper. In order to cause the upper pressing face of the claw to remain substantially horizontal during its rising and falling movements, the rod 141 on which it is secured has secured on it, to the left of its bearing sleeve, a short vertical link 151 which, at its upper end, encircles a short rod 153 lying parallel to the rod 141 and secured in a pair of spaced ears 155 projecting forwardly from a short link 157 extending rearwardly parallel to the forward portion of the lever 143, said link being pivotally mounted at its rear end on a fixed transversely extending pin 159 positioned over the pin 145 on which the lever 143 is pivoted.

This arrangement, therefore, provides a parallel linkage by which the upward and downward movements of the upper pressing claw take place without causing its work pressing face to deviate out of its normal horizontal position.

It is desired that the claw, the two limbs of which, as above stated, lie close against the opposite sides of the needle, should move laterally with the latter as the latter feeds the work and while the claw is pressing against the overlying margin of the upper. For this purpose, the rod 141 extends so far over towards the left of the machine as to lie behind the lower end of a lever 161 which, through mechanism similar to that disclosed in Patent No. 2,067,649 imparts the lateral movements to the needle 1, the rod 141 lying substantially in the same horizontal plane as the needle axis. The lower end of the lever 161 embraces the opposite sides of a trunnion block 163 mounted on the needle actuating shaft and this trunnion block has extending rearwardly from it a pin 165 which enters a hole in a block 167 slidably between vertical ears 169 formed on the forward side of the short link 157 which is secured on the rod 141 and by this means the claw 9 is caused to move to and fro laterally with the needle.

The upper-pressing claw 9 is arranged to descend upon the work, before the needle pierces it, to press the portions of the margin of the upper close against the opposite sides of the needle firmly against the sole and to assist in supporting the margins of the upper and sole against being bent upwardly, then to move laterally with the needle, while still bearing on the upper face of the work, as the latter feeds the work, to remain pressing the upper against the sole as the needle retreats from the work to support the margin of the upper against being torn or raised away from the sole by the barb of the needle, and finally to rise away from contact with the upper after the needle has retired from the work and to move idly back towards the right with the latter preparatory to the formation of another stitch.

For the purpose of actuating the claw to press on the margin of the upper in a firm, but yielding, manner, the cam-actuated lever 149 which acts at its forward end on the lever 143 carrying the claw extends rearwardly from its connection with the lever 143 and is pivoted near its rear end on a fixed transversely extending rod 171. The rear end of the lever 143 carries a cam roll 173 engaging the periphery of a cam on the cam shaft of the machine. The lever 149 actually comprises two parts, both being pivoted on the rod 171, one 175 extending forwardly from the rod, and the other 177, which carries the cam roll 173,

extending rearwardly from the rod. The latter part 177 has projecting forwardly of the rod 171 an upper lug 179 and a lower lug 181 spaced apart vertically in the machine. The forwardly extending part 175 of the lever 149 has housed in it a downwardly and rearwardly extending spring plunger 183 which bears on the upper face of the lower lug 181 and raises the forwardly extending part 175 of the lever relatively to the rearwardly extending part 177 until a stop face 185 on the forwardly extending part projecting between the lugs 179, 181 abuts against an adjustable set screw threaded into the upper lug 179.

By this means downward rocking movement of the rearwardly extending part 177 of the lever 149 effected by the cam, imparts a yielding upward movement to the forward part 175 of the lever and thus urges the claw 9 yieldingly but firmly down against the work.

During the downward movement of the rear part 177 of the lever 149 under the action of its cam, the latter first commences to raise the forward part 175 of the lever through the spring plunger 183 in the latter and thereby to urge the claw 9 yieldingly but firmly against the upper. The rear part 177 of the lever thereafter continues to descend and the screw in the upper lug 179 on the latter, commences to ride away from contact with the stop face 185 on the forward part 175 of the lever as the spring behind the spring pressed plunger 183 continues to yield.

In case it should be desired to retain the sole-engaging foot 71 previously described, as close against the right hand side of the needle as possible, i. e., in case it is preferred not to move it towards the right to make room for the right hand limb of the claw 9, the latter may have its right hand limb removed so as to obviate the necessity for the foot 71 to be removed towards the right far enough to make room for this limb.

In order to prevent undesirable particles of material such as fluff or dust which are formed during the sewing operation from falling into and clogging the mechanism at the base of the external work support 33 there is provided a guard 187 at the last mentioned locality. The guard 187 is formed in two parts which are each supported on the upper end of a slide 189 secured for vertical sliding movement on the forward face of the bracket 11. Pins 191 extending rearwardly of the machine from the upper end of the slide 189 form pivots upon which the two parts of the guard may pivot to each side of the work support when it is desired to inspect the mechanism they normally shroud. As seen in Figure 1, bosses formed on the forward end of the lever 55 engage in slots cut in upstanding webs 193 on the slide 189, thereby causing the slide and the guard it carries to rise or fall with the forward end of the lever 55 as the work support rises or falls due to breaking of the toggle device 65, 67 or to adjustment of the screw 17. A leaf spring 195 secured to one half of the guard 187 engages the other half and prevents either part from unintentional separation about the pivots 191.

Since the machine comes to rest with the pleater 7 advanced to a position in which its forward end lies over and almost in contact with the sole-engaging foot 71 and in which position of the pleater presentation of a shoe to the machine may be difficult, means is provided for causing the pleater 7 to be retracted to a position away from over the sole engaging foot at the same time as the work support is lowered for the presentation 75

of a shoe to the machine by the operator. This means comprises a lever 197 which extends rearwardly from a short shaft 199 which is secured in the lever 197 and also in the lower end of the 5 lower member 67 of the toggle device 65, 67. At its rear end, the lever 197 is connected to the lower end of a substantially vertical rod 201 which, at its upper end is pivotally connected to the forward end of a rearwardly and downwardly 10 extending lever 203 which is pivoted between its ends on a pin 205 secured in the machine frame. The rear end of the lever 203 carries a short pin 207 extending towards the right of the machine which engages in a slot cut in a forwardly ex- 15 tending arm of a bell crank lever 209 pivoted to the machine frame. The other arm of the bell crank lever extends upwardly and has a rearwardly directed face thereon which contacts with a transversely extending pin 211 secured near 20 the lower end of a depending pleater operating cam lever 213. The said cam lever 213 is connected at its lower end by means of a ball joint to the rear end of a forwardly and rearwardly 25 extending rod 215 which, at its forward end is connected by a universal joint to a slide 217 which carries the pleater 7 and is slidable in the guide-way 114 aforementioned.

As has been previously mentioned, the pleater normally occupies its forward position when the 30 machine comes to rest, but when the lower member 67 of the toggle device aforementioned is caused to swing about the axis of the rod 199 to break the toggle device and lower the work support 33 for the presentation of a shoe to the ma- 35 chine, the lever 197 is also swung downwardly and through the rod 201 and lever 203 causes the bell crank lever 209 to be swung in a clockwise direction, as seen in Figure 2. As the bell crank lever 209 so swings the rearwardly directed face aforementioned on the upwardly extending arm 40 of the bell crank lever engages the pin 211 and causes the cam lever 213 to be swung rearwardly against the action of a spring 219 coupled to it to withdraw the pleater to a position well removed 45 from that which it would normally occupy, thus allowing of the easy presentation of a shoe to the machine.

Referring now to the embodiment of the several features of the invention illustrated in Figures 7 to 11, the machine illustrated in these figures is similar in many respects to that disclosed in the patent to Bates, No. 1,898,521 dated February 21, 1933. In embodying, in a machine of the type disclosed in this patent, supporting and actuating mechanism for a needle of relatively short radius, it has been found desirable to modify the looper mechanism so as to cause its thread guiding eye to move, as it loops the needle, in a path more nearly perpendicular to the end of the 50 needle protruding through the work. Accordingly, in the machine illustrated in Figures 7 to 11, a looper mechanism is provided which comprises, as seen in Figures 7 and 10, a bell crank lever 251 operated by a cam 253 and a lever 255 mounted on the bell crank lever 251 and operated by another cam 257 on the cam shaft of the machine. Instead of mounting the looper directly upon the lever 255, the looper is carried at the 55 lower end of a pendulous lever 259 to which the lever 255 is connected by a ball joint coupling 261 arranged forwardly of the pivotal connection of the lever 255 with the lever 251 and near the lower end of the pendulous lever 259. The pendulous lever 259 extends substantially vertically, 60 considered both forwardly and rearwardly, and

laterally of the machine, and at its upper end is connected, by a pivot 263 extending forwardly and rearwardly of the machine, to the right hand end of a transversely extending horizontal rod 265 which is mounted, with freedom for rotation, in a bearing in a fixed bracket 267. Towards its lower end the lever has secured in ears thereon a pin 269 which lies perpendicularly to the downwardly and forwardly sloping lever 255 and this pin has a spherical sleeve portion 271 slidably 10 mounted between its ends which is embraced by a spherical seating formed in a member 273 secured in the forward end of the lever 255. The lower end of the pendulous lever 259 has secured to it by means of a bolt 275 a downwardly ex- 15 tends looper 277 which is curved rearwardly towards its thread-guiding eye 279 which latter normally lies slightly rearwardly of the vertical plane containing the pivot rod 265 at the upper 20 end of the lever 259. By reason of this arrangement, rocking of the bell crank lever 251 will impart forward and rearward movement to the thread-guiding eye 279 of the looper 277 and lateral rocking movement of the lever 255 will impart the desired lateral movement to the thread-guiding eye. As the levers 251 and 255 cooperate to move the thread-guiding eye 279 to lay the thread in the needle barb, the pendulous lever 259 swings both laterally and forwardly and rearwardly about its upper end and the thread-guiding eye moves in a curved path which neither rises nor falls appreciably considered either forwardly and rearwardly or laterally of the machine, i. e., the eye moves, in passing around the needle, in a path which remains substantially in 30 a horizontal plane. Since the pointed end of the needle above the barb will be extending upwardly more or less vertically at the time of looping, the thread-guiding eye 279 of the looper 277 will move more or less perpendicularly to this portion of the needle, the lower end of the eye actually passing just below the barb, and will therefore lay the thread around the needle in such a manner that it can hardly fail to be properly 35 pulled rearwardly through the work by the barb 40 as the needle retreats through the work. 45

Conveniently, since there exists but little room, owing to the shortness of the needle radius, between the point of the needle 1 and the sector 281 to which the latter is secured within which the eye of the looper may dwell as the sector swings forwardly to retract the needle from the work, the cams 253, 257 controlling the looper are so shaped that the eye 279 of the looper is moved sufficiently far forwardly and towards the right in looping the needle that, at the time when the sector starts to swing forwardly, the eye of the looper lies in front and to the right of the sector and is, therefore, not liable to be struck by it. Moreover, in order that the looper 50 may direct the thread in the most desirable manner as the needle pulls the needle loop through the work, the cams are so shaped that the eye of the looper moves to a position in front of the needle soon after the needle has commenced to 55 retire from the work and thus causes the thread extending from the looper to the needle to extend in a path lying substantially in the plane in which the needle lies.

The mechanism for actuating the needle of 70 the machine illustrated in Figures 7 to 11 is generally similar to that disclosed in Patent No. 2,067,649. The mechanism for moving the needle laterally of the machine to effect the feeding of the work, however, includes an adjustable 75

- linkage arrangement interposed between a cam lever 283 and a link 285 (Figure 8) which transmits the movements of said lever to a needle carriage 286, which linkage arrangement is connected to a treadle by which it can be adjusted during the operation of the machine to vary the extent of the work feeding movements of the needle and, therefore, the length of the stitches made in the work. Depression of the treadle 10 serves to vary the position laterally of the machine which the needle occupies when it strikes into the work, the needle reaching a constant position towards the left at the end of its feeding movement whatever be the length of stitch 15 it makes in the work. The treadle is actually connected through a treadle rod 287 to one arm 289 of a bell crank lever secured on the rear end of a forwardly and rearwardly extending shaft 291, the other arm 293 of said bell crank 20 lever supporting a pivoted link 295 which, at its opposite end is connected to the right hand end portion of the jointed link 285, and also to another link 297 connected to an arm on the cam lever 283 forming a connection between the cam lever 283 and the jointed link 285 connected to the needle carriage 286. The connection of the jointed link 285 to the needle carriage 286 comprises an arm 299 depending from and fixedly secured to the rear end of a forwardly and rearwardly extending rock shaft 301, the lower end of said arm being connected to the right hand end portion of the jointed link 285. Depending from and fixed to the forward end of the rock shaft 301 is another arm 303 which at its lower 30 end is forked to embrace the opposite sides of a square block 305 rotatably secured on a pin 307 fixed in the feed carriage 286. As the jointed link 285 is reciprocated transversely of the machine by the cam lever 283, as hereinbefore described, the lever 303 will be rocked to and fro to impart through the feed carriage 286 the work feeding movements to the needle 1. Rocking of the bell crank lever 289, 293 through the treadle 40 adjusts the position of the pivoted link 295, and by the consequent variation in the direction in which the latter is swung by the cam lever 283 through the link 297, varies the extent of lateral movement imparted to the needle.
- To limit the rocking movement of the shaft 291, and thus the extent of the feeding movement imparted to the needle, an arm 323 is secured to the forward end of the shaft 291 and is arranged to move between a pair of spaced pins 325 plugged into two of a series of holes 327 of the fixed sector 329 on the machine frame. By means of this arm 323, pins 325 and sector 329, the extent of rocking movement of the needle may be limited by the operator as may be deemed most suitable for the particular requirement then existing.
- When an adjustment is made in the extent of the feeding movement imparted to the needle, it is desirable that a corresponding adjustment of the sole engaging foot 331 and also of the pleater 7 be made in the line of feed, in order to maintain these parts in the most advantageous position with relation to the needle. To this end the machine is provided with a bracket 309 slidably mounted on the frame of the machine 50 so as to be movable back and forth in the direction of feed. This bracket is provided with an extension 313 which is adjustable back and forth in the direction of feed on the bracket. A pin 311 extends rearwardly from the extension 313 55 and engages a slot 301 formed in a cam mem-
- ber 319 secured to the arm 323 which, as above stated, is rigidly secured to the adjusting rock shaft 291. The arrangement thus is such that when the shaft 291 is rocked to adjust the extent of needle feed, the bracket 309 is also moved laterally of the machine, a distance substantially equal to the lateral displacement of the needle effected by the rocking of the shaft, the movement of the bracket 309 taking place in the same direction as the movement of the needle. The initial position of the bracket 309 can be varied by means of the adjustable connection between the extension 313 and the bracket 309, which adjustable connection comprises an eccentric pin 315 mounted in the extension 313 and carrying a block engaging a vertical slot in the bracket 309. After adjustment, the extension is locked in position by means of a bolt passing through a horizontal slot 317 in the bracket 309.
- On the bracket 309 there is adjustably secured a sole engaging foot 331 (see Figures 7 and 9) of the same shape and character as the foot 71 previously referred to, this foot normally occupying a position close by the right hand side of the needle 1 as does the sole engaging foot 71. By reason of the fact that the bracket 309 is adjusted laterally with the needle on depression of the treadle to vary the stitch length the result is obtained that the sole engaging foot 331 retains its position close against the needle in spite of the adjustment in the lateral position of the latter, thus giving the advantage that whatever be the length of stitch being made, the sole engaging foot will always support the work as close to the side of the needle as possible. The sole 35 engaging foot 331 is adjustably mounted upon a second bracket 333, secured by means of a horizontal transversely extending bolt 334 to a face formed on the left hand side of the bracket 309, in a similar manner to that in which the sole engaging foot 71 is mounted upon the lower end of the lever 75. A rearwardly extending pin 335 projecting from a block 337 carrying the foot and passing through a horizontal bore in the bracket is connected at its rear end by a pin 339 to a small bell crank lever 341 coupled by a rod 343 to the lever (see Figure 2) which is arranged to be raised and lowered by rocking movement of the cam plate 107 controlled by the hand lever 109. A second pin 345 lying parallel with and above the pin 335 is located between two sides of a slot in the upper face of the bracket 333 and prevents the block 337 from turning about the axis of the pin 335. Another pin 347 projecting from the face on the bracket 309 to which the bracket 333 is secured, into a slot formed in the bracket 333 serves to locate the latter in correct relation to the bracket 309. By the aforementioned means, the foot 331 can be moved forwardly in a manner similar to the foot 71 previously mentioned to allow the initial stitches of a seam to pass by its rearward end to facilitate the overlapping of the beginning and end of the seam at the completion of the sewing operation. It will, of course, be understood that the sole engaging foot 331 normally extends rearwardly close against both the edge of the sole and the operative face of an edge guide 29 as does the sole engaging foot 71 first mentioned.
- If it is desired to sew shoes having channelled soles the sole engaging foot 331 may be removed from the bracket 309 by the unclamping of the bolt 334 which secures the bracket 333 and thus also the foot 331 to the bracket 309 and a chan-

nel guide holder 349 (see Figure 11) may be secured to the block 309 in its place by means of a stud 351, which takes the place of the bolt 334, in such a manner that it may rock about a trans-
5 verse axis.

The stud 351 is rotatable within the bore into which the bolt 334 had previously passed and has an eccentric left hand end portion which is clamped by means of a small bolt 353 within a 10 bore formed in the holder 349. The channel guide holder has a downwardly extending bore formed in it into which passes the stem of a channel guide 355. A nut 357 threaded upon the upper end of the stem of the channel guide and 15 located between the sides of a slot cut in the holder 349 provides an adjustment whereby the channel guide may be set to any desired height-wise position, a set screw 359 serving to maintain such adjustment upon being tightened upon 20 the stem of the channel guide.

Projecting from the holder 349 is a short rearwardly and upwardly extending arm 361 the upper end of which is slotted to house a rectangular block 363 pivoted on the lower end of a 25 lever 365 actuated by a cam on the main shaft of the machine. The channel guide is thus actuated to rock about the axis of the stud 351 and, by reason of the connection with the cam operated lever 365 it is moved forwardly a short distance before each lateral feeding movement of 30 the needle takes place to relieve its pressure against the root of the channel lip to facilitate the feeding of the work.

The guide 114 for the pleater 1 is supported by 35 the bracket 309 which carries the sole engaging foot 331 or the channel guide 355 as the case may be, and since this bracket is adjusted laterally of the machine with the needle in the manner previously referred to, the result is obtained that whenever a change in the feed length is 40 made, both the sole engaging foot 331 or channel guide 355 and the pleater 1 retain their original positions close by the side of the needle 1, thus ensuring that the pleater will operate to 45 form the pleats on the work at the most desirable position relatively to the needle, it actually advancing as previously described over the rearward end of the sole engaging foot 331 when this is used and, when the channel guide has been substituted for that foot, the pleater operating to 50 lay the margin of the upper directly against the margin of the sole.

In Figures 12 to 15 is illustrated an external work supporting structure embodying the principal novel features of the structure illustrated 55 in Figure 2 hereinbefore described, but modified to render it simpler, stronger, more durable and better adapted for high speed operation.

In this construction the external work support, indicated at 365, is mounted on the rear ends of substantially parallel links, the forwards ends of which are pivoted on a vertically yielding supporting frame. The parallel links upon which the work support 365 is mounted comprises two 60 links 369 arranged side by side and pivoted at their rear ends to the mid-portion of the support 365 and a curved link 371 lying below the links 369 and pivoted at its rear end to the lower end of the work support 365. At their forward ends, the links 369 and 371 are pivotally 65 mounted on the forward ends of rearwardly extending and substantially parallel links 373 and 375 which, at their rear ends, are pivoted to the main frame of the machine at 377 and 379. At 70 their forward ends the links 373 and 375 are

connected by a link 381 so that the links 373, 375 and 381 form a supporting frame or carrier mounted for vertical movement on the main frame of the machine. At its forward end, this carrier is yieldingly supported, as will be herein-
5 after described.

Midway of the link 371 and pivoted thereto is a link 383 which extends rearwardly to connect with the lower end of an arm 385 depending from a rock shaft 387. A forwardly and 10 downwardly extending arm 389 also fast on the rock shaft 387 is connected to the lower end of a cam-operated rod 391 corresponding to the rod 23 of the construction illustrated in Figure 2. The arrangement of the parts just described is 15 such that rising and falling movements of the rod 391 cause rocking of the shaft 387 which, through the arm 385 and link 383, imparts turning movements to the link 371 about the pivotal connection at its forward end with the forward 20 ends of the link 375. The link 371 is somewhat shorter than the links 369, and the proportion and arrangements of the links 371 and 369 are such that rising and falling movements are imparted to the work support 365 and also oscillating movements about the pivotal connection of the support with the link 369. As a result of these movements, the upper end of the support 365 moves in a path very similar to that of the upper end of the support 33 illustrated in Figure 2 30 and hereinbefore described.

As has been stated, the frame or carrier comprising the links 373, 375 and 381 is yieldingly supported at its forward end, means being provided for adjusting the height of the forward 35 end of the frame, and thus also the height of the work support 365 indirectly carried thereby. By supporting the forward end of the frame yieldingly a means is provided whereby the work support 365 may yield in its upward movement 40 should it commence to press the sole of a shoe upwardly in too firm a manner. To support the forward end of the frame, a pair of ears 393 project forwardly from the mid-portion of the link 381 and embrace opposite sides of a threaded 45 trunnion sleeve 395. Threaded into this sleeve 395 and extending downwardly therefrom is the upper and reduced end of another sleeve 397, a thin washer 399 secured to the upper face of the sleeve serving to prevent the latter from being 50 unscrewed out of engagement with the trunnion sleeve 395. A vertical rod 401 passing axially through the sleeve 397 and provided with nuts 403 on its upper end is located at its lower end in normally fixed relation to the frame of the machine and serves by means of the said nuts to 55 locate the sleeve 397 in a vertical position relatively to the machine frame. A spring 405 bears at its upper end against a shoulder formed inside the sleeve 397 and serves to hold the upper face 60 of the sleeve against the lower end of the nuts 403 in a yielding manner. Should the resistance encountered by the support 365 become excessive the link 381 will be urged downwardly and through the trunnion sleeve 395 and the sleeve 65 397 compress the spring 405. By turning the sleeve 397 the trunnion sleeve 395 may be caused to take up a position higher or lower on the threaded portion of the sleeve 397 and since the latter remains in a fixed vertical position (unless caused to yield as just described) serves to 70 impart initial vertical adjustment to the support 365. The lower end of the vertical rod 401 is of considerably increased diameter and is housed in the lower end of another sleeve 407 which at 75

this locality is pivotally mounted in a pair of transversely extending pins 409 secured in the machine frame. A reduction in the diameter of the bore in the sleeve 407 provides a shoulder 5 411 against which the enlarged portion of the vertical rod 401 normally abuts to prevent the latter being displaced upwardly by the spring 405. That portion of the sleeve 407 which extends above the locality where the bore is reduced is threaded externally and carries thereon an adjusting sleeve 413 which at its upper end is taper bored to engage a corresponding surface on the upper end of yet another sleeve 415, a reduced and lower portion of this sleeve being 10 received within the bore in the sleeve 407. A pin 417 threaded into the sleeve 415 and extending into a vertical slot 419 in the sleeve 407 limits relative turning movements of the sleeves whilst allowing of relative axial displacement. As the 15 sleeve 413 is adjusted to a position further up or lower down the sleeve 407, the sleeve 415 through its engagement with the taper bore in the sleeve 413 will be likewise adjusted, an internal shoulder formed therein which provides a 20 seating for the lower end of the spring 405 serving to increase or decrease the amount of compression in the latter. The taper bore and the corresponding face it engages with aforementioned also serve as a friction device to prevent 25 unintentional rotation of the adjusting sleeve 413, whilst the trunnion sleeve 395 is split vertically at its forward side and is clamped by means of a screw 421 upon and thus prevents rotation of, the sleeve 397. Graduations marked 30 around the periphery of the adjusting sleeve 413 serve to give an indication of the amount of compression the spring receives as the sleeve 413 is rotatably adjusted and also of the amount of yield taking place as the support 365 rises to 35 clamp the work. The enlarged lower end of the vertical rod 401 is slotted in a direction forwardly and rearwardly of the machine to provide a pair of ears 423 through which (at right angles to the slot) a pin 425 is located to engage 40 a forked end of a rearwardly extending lever (not shown) which, when rocked in a suitable direction by treadle or other mechanism, causes the rod 401 to be drawn downwardly. By means of the nuts 403 threaded upon the upper 45 end of the rod, the link 381 will also be lowered as before described, this movement being transmitted to the support 365 to enable work to be presented to the machine at the commencement of the sewing operation.

50 The nature and scope of the several features of the invention having been indicated, and embodiments of the invention having been specifically described, what is claimed is:

1. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, and means for actuating the work support to move its work engaging surface away from said last mentioned sole surface and transversely of the direction of feed away from the center line of the shoe during each stitch forming and work feeding cycle to relieve the pressure of the work support on the upper during the feed of the work.
2. A machine for sewing together a shoe sole

and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, and means for actuating the work support to move its work engaging surface away from said last mentioned sole surface in a path substantially perpendicular to said surface and then transversely of the direction of feed away from the center line of the shoe in a path substantially parallel to said surface during each stitch forming and work feeding cycle to relieve the pressure of the work support on the upper during the feed of the work.

3. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, a carrier on which the work support is mounted, means for moving the carrier with the work support towards and away from said last mentioned sole surface, and connections actuated from the carrier during its movement away from said sole surface for actuating the work support to move its work engaging surface transversely of the direction of feed away from the center line of the shoe.

4. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, a carrier upon which the work support is pivotally mounted, means for moving the carrier with the work support towards and from the work, a cam plate pivotally mounted in the carrier, and connected to the work support, and means for swinging the cam plate about its pivot during the movement of the carrier away from the work to swing the work support about its pivotal connection with the carrier and move the work engaging surface of the work support transversely to the direction of feed away from the center line of the shoe.

5. A machine for sewing together a shoe sole and the overlapping margin of the upper while unsupported on a last, having in combination, stitch forming and work feeding devices including a curved needle arranged to pass through the upper and enter a margin from one surface of the sole, an external work support arranged to move towards and from the other sole surface opposite the sewing point, and links on which the support is mounted proportioned and arranged to cause the work engaging surface of the work support to move away from said last mentioned sole surface, in a path extending transversely of the direction of feed and away from the center line of the shoe.

6. A machine for sewing together a shoe sole and the overlapping margin of the upper while unsupported on a last, having in combination, stitch forming and work feeding devices including a curved needle arranged to pass through the upper and enter a margin from one surface of

- the sole, an external work support arranged to move towards and from the other sole surface opposite the sewing point, and links on which the support is mounted proportioned and arranged to cause the work engaging surface of the work support to move away from said last mentioned sole surface in a path extending substantially perpendicular to said surface and then transversely of the direction of feed away from the center line of the shoe and parallel to said surface.
7. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, a carrier upon which the external work support is mounted, mechanism unconnected with the carrier for moving the work support towards and from the work, and a spring supporting the carrier and permitting the carrier to yield after the work support engages the work.
8. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, a carrier upon which the external work support is mounted, mechanism unconnected with the carrier for moving the work support towards and from the work, a spring supporting the carrier and permitting the carrier to yield after the work support engages the work, and means for adjusting the tension of the spring while maintaining the carrier at the same distance from the work.
9. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, a carrier upon which the external work support is mounted, mechanism unconnected with the carrier for moving the work support towards and from the work, a spring supporting the carrier and permitting the carrier to yield after the work support engages the work, and means for adjusting the carrier towards and from the work while maintaining a constant tension on the spring.
- 60 10. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, a carrier upon which the external work support is mounted, mechanism unconnected with the carrier for moving the work support towards and from the work, a spring supporting the carrier and permitting the carrier to yield after the work support engages the work, and means for independently adjusting the

tension of the spring and the distance of the carrier from the work.

11. A machine for sewing together a shoe sole and the overlapping margin of an upper while unsupported on a last having, in combination, stitch forming and work feeding devices including a curved needle arranged to pass through the upper and enter and emerge from one surface of the sole, an external work support arranged to press the upper against the other sole surface opposite the sewing point, substantially parallel links on which the support is mounted, a carrier on which the links are mounted comprising parallel links, a fixed support for one end of the links, and means for yieldingly supporting the other end of the links.

12. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface and provided with a portion extending beneath the overlapping margin of the upper into proximity with the edge of the sole, and an external work support arranged to press the upper against the other sole surface opposite the work engaging surface of the presser-foot, said work support being provided with a work engaging surface extending substantially to the edge of the shoe sole.

13. A machine for sewing together a shoe sole and the overlapping margin of an upper while unsupported on a last having, in combination, stitch forming and work feeding devices including a curved needle arranged to pass through the upper and enter and emerge from one surface of the sole, a pressure-foot engaging said surface and provided with a portion extending across the line of the seam, and means for supporting said presser-foot permitting a movement of the presser-foot transversely of the seam line near the end of the sewing of a seam in which the beginning and end stitches overlap.

14. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface and provided with a portion extending across the line of the seam, and means for moving said presser-foot transversely of the seam line during the continued operation of the machine in finishing a seam in which the beginning and end stitches overlap.

15. A machine for sewing together a shoe sole and the overlapping margin of an upper while unsupported on a last having, in combination, stitch forming and work feeding devices including a curved needle arranged to pass through the upper and enter and emerge from one surface of the sole, means for actuating the needle to feed the work having provision for adjustment to vary the extent of feeding movement, a presser-foot engaging said surface provided with a portion extending transversely of the line of feed in close proximity to the needle, and means for adjusting the presser-foot in the line of feed.

16. A machine for sewing together a shoe sole and the overlapping margin of an upper while unsupported on a last having, in combination, stitch forming and work feeding devices including a curved needle arranged to pass through

- the upper and enter and emerge from one surface of the sole, means for actuating the needle to feed the work having provision for adjustment to vary the extent of feeding movement, a presser-foot engaging said surface provided with a portion extending transversely of the line of feed in close proximity to the needle, and connections for adjusting the presser-foot in the line of feed simultaneously with an adjustment of the feeding movement of the needle.
17. A machine for sewing together a shoe sole and the overlapping margin of an upper while unsupported on a last having, in combination, stitch forming and work feeding devices including a curved needle arranged to pass through the upper and enter and emerge from one surface of the sole, means for actuating the needle to feed the work, a presser-foot engaging said sole surface, and an upper presser to press the upper against said surface mounted to move with the needle in the line of feed.
18. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface, an upper presser to press the upper against said surface provided with an upper engaging face parallel to the sole engaging face of the presser-foot and means for actuating the upper presser to engage the upper prior to the entrance of the needle into the work.
19. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface, an upper presser to press the upper against said surface, and means for moving the upper presser into and out of pressing engagement with the upper during each stitch forming cycle prior to the entrance of the needle into the work while maintaining the upper engaging face of said presser parallel with the sole surface.
20. A machine for sewing together a shoe sole and the overlapping margin of an upper while unsupported on a last having, in combination, stitch forming and work feeding devices including a curved needle arranged to pass through the sole, a presser-foot engaging said surface, an upper presser to press the upper against said surface, and cam actuated means comprising a yielding connection for moving the upper presser into and out of pressing engagement with the upper during each stitch forming cycle.
21. A machine for sewing together a shoe sole and the overlapping margin of an upper while unsupported on a last having, in combination, stitch forming and work feeding devices including a curved needle arranged to pass through the upper and enter and emerge from one surface of the sole, means for actuating the needle to feed the work, a presser-foot engaging said sole surface, an upper presser to press the upper against said surface mounted to move with the needle in the line of feed, and means for moving the upper presser into and out of pressing engagement with the upper during each stitch forming cycle.
22. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface, a pleater mounted to move while in engagement with the upper transversely to the line of feed to form a pleat in the upper, actuating mechanism for so moving the pleater during each stitch forming cycle, means for actuating the needle to feed the work having provision for adjustment to vary the extent of feeding movement, and means for adjusting the pleater in the line of feed.
23. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface, a pleater mounted to move while in engagement with the upper transversely to the line of feed to form a pleat in the upper, actuating mechanism for so moving the pleater during each stitch forming cycle, means for actuating the needle to feed the work having provision for adjustment to vary the extent of feeding movement, and connections for adjusting the pleater in the line of feed simultaneously with an adjustment of the feeding movement of the needle.
24. A machine for sewing together a shoe sole and the overlapping margin of an upper while unsupported on a last having, in combination, stitch forming and work feeding devices including a curved needle arranged to pass through the upper and enter and emerge from one surface of the sole, means for actuating the needle to feed the work having provision for adjustment to vary the extent of feeding movement, a presser-foot engaging said surface provided with a portion extending transversely of the line of feed in close proximity to the needle, a pleater mounted to move while in engagement with the upper transversely to the line of feed to form a pleat in the upper, actuating mechanism for so moving the pleater during each stitch forming cycle, and means for adjusting the presser-foot and pleater in the line of feed.
25. A machine for sewing together a shoe sole and the overlapping margin of an upper while unsupported on a last having, in combination, stitch forming and work feeding devices including a curved needle arranged to pass through the upper and enter and emerge from one surface of the sole, means for actuating the needle to feed the work having provision for adjustment to vary the extent of feeding movement, a presser-foot engaging said surface provided with a portion extending transversely of the line of feed in close proximity to the needle, a pleater mounted to move while in engagement with the upper transversely to the line of feed to form a pleat in the upper, actuating mechanism for so moving the pleater during each stitch forming cycle, and connections for adjusting the presser-foot and pleater in the line of feed simultaneously with the adjustment of the feeding movement of the needle.
26. A machine for sewing together a shoe sole and the overlapping margin of an upper while unsupported on a last having, in combination, stitch forming and work feeding devices including a curved needle arranged to pass through the upper and enter and emerge from one surface of the sole, a presser-foot engaging said surface, a pleater mounted to move while in engagement with the upper transversely to the line of feed to form a pleat in the upper, actuating mechanism for so moving the pleater during each stitch forming cycle, and connections for adjusting the presser-foot and pleater in the line of feed simultaneously with the adjustment of the feeding movement of the needle.

upper and enter and merge from one surface of the sole, a presser foot engaging said surface, a pleater mounted to move while in engagement with the upper transversely to the line of feed to 5 form a pleat in the upper, actuating mechanism for so moving the pleater during each stitch forming cycle, and means for retracting the pleater from the position to which it is moved by its actuating mechanism, as the machine 10 comes to rest.

27. A machine for sewing together a shoe sole and the overlapping margin of an upper while unsupported on a last having, in combination, stitch forming and work feeding devices including 15 a curved needle arranged to pass through the upper and enter and emerge from one surface of the sole, an external work support arranged to press the upper against the other sole surface opposite the sewing point, a pleater mounted to 20 move while in engagement with the upper transversely to the line of feed to form a pleat in the upper, actuating mechanism for so moving the pleater during each stitch forming cycle, means for moving the work support away from said last 25 mentioned sole surface to permit the removal and insertion of work, and connections for simultaneously retracting the pleater from the position to which it is moved by its actuating mechanism.

28. A machine for sewing together a shoe sole 30 and the overlapping margin of an upper while unsupported on a last having, in combination, stitch forming and work feeding devices including a curved needle arranged to pass through the upper and enter and emerge from one surface of 35 the sole, an external work support arranged to press the upper against the other sole surface opposite the sewing point, a pleater mounted to

move while in engagement with the upper transversely of the line of feed, to form a pleat in the upper, actuating mechanism for so moving the pleater during each stitch forming cycle, and a treadle and suitable connections for moving the work support away from said last mentioned surface to permit the removal and insertion of work, and for retracting the pleater from the position to which it is moved by its actuating mechanism. 5

29. A machine for sewing together a shoe sole 10 and the overlapping margin of an upper while unsupported on a last having, in combination, stitch forming and work feeding devices including 15 a curved needle arranged to pass through the upper and enter and emerge from one surface of the sole, a lever having provision at one end for mounting thereon alternatively a presser-foot and a channel guide, a cam arranged to act on said lever to move said end of the lever transversely to the line of feed during each stitch 20 forming cycle, and a latch for holding the lever out of operative relation to the cam.

30. A machine for sewing together a shoe sole 25 and the overlapping margin of an upper while unsupported on a last having, in combination, stitch forming and work feeding devices including 30 a curved needle arranged to pass through the upper and enter and emerge from one surface of the sole, a lever having provision at one end for mounting thereon alternatively a presser-foot and a channel guide, a cam arranged to act on 35 said lever to move said end of the lever transversely to the line of feed during each stitch forming cycle, and means for preventing actuation of the lever by the cam.

ROWLAND AUGUSTUS LINEHAM.
FRANK BARTON.
